UNITED STATES PATENT OFFICE

ARTHUR F. PYM, OF SWAMPSMOTT, MASSACHUSETTS, ASSIGNOR TO UNITED SHOE MANUFACTURING CORPORATION, OF PATERSON, NEW JERSEY, A CORPORATION OF NEW JERSEY

LEVELING MACHINE

Application filed June 7, 1928. Serial No. 283,551.

This invention relates to machines for operating on boots and shoes to perform what is commonly termed the leveling operation, whereby the sole is shaped to the contour desired for the finished shoe. It is one of the objects of the invention to provide improved means for shaping the soles of turn shoes, and more particularly the shank portions of the soles, and the invention is accordingly illustrated in its application to a machine constructed especially for that purpose. It will be recognized, however, that in various novel aspects the invention is not limited to machines for operating upon turn shoes or to means for shaping that particular portion of the sole.

In order to shape or level satisfactorily the sole of a turn shoe, it is necessary to subject the sole to such treatment as to flatten the seam whereby the upper is secured to the sole, to remove irregularities which are likely to be especially prominent in the shank portion of the sole, and in general to conform the sole to the transverse curvature of the bottom of the last which is especially pronounced also at the shank. At the same time, it is necessary to guard against undue stretching in the direction of its length or otherwise distorting or injuring the single sole with which this type of shoe is provided, as might result, for example, from the use of heavy rolling pressure such as it is customary to use in leveling welt shoes.

In view of these considerations, it has been found that in leveling the sole of a turn shoe, especially in the shank, it is desirable to subject the sole to a plurality of pressure impulses applied in directions heightwise of the shoe, as by beating or pounding it. An object of the present invention, accordingly, is to provide improved means for treating shoes in this manner, and for the purposes in view the invention provides a novel organization of means for applying repeated pressure impulses to the bottom of a shoe and means for supporting and controlling the shoe to present it in such relation to the pressure-applying or leveling tool as to secure the desired results. The machine herein shown as an illustrative embodiment of the various fea-

tures of the invention comprises a shoe support or jack which may be moved by power at the will of the operator in directions lengthwise of a shoe thereon to cause the tool to traverse the bottom of the shoe and by the use of which the shoe may also be tipped or inclined laterally as desired to vary its relation to the tool, in combination with a power-operated leveling tool which is reciprocated heightwise of the shoe to deliver repeated blows upon the shoe bottom under such control that its operation may be started and stopped at the will of the operator independently of the movement of the shoe support. The operator is thus enabled readily to determine and vary the position of the shoe in relation to the leveling tool and to cause different portions of the shoe bottom to be subjected to varying amounts of pounding treatment as conditions may render desirable.

While in some of its aspects the invention is not limited in respect to the character of the leveling tool, it is for some reasons considered preferable to use a roll so mounted as to permit it to turn about an axis extending laterally of the shoe in response to engagement of the shoe therewith. Among other advantages, this serves to avoid undue strain on the sole in the direction of its length, such as might result from rubbing pressure, especially in operating upon the upwardly sloping portion of the sole at the rear of the ball-line where, in shoes having high-arched shanks, the direction of the beating movement of the tool is at a substantial inclination to the length of the sole.

For the particular purpose of operating upon the comparatively narrow shank portion of a sole having a pronounced lateral curvature, as in a turn shoe, the roll illustrated is further provided with a V-shaped recess extending about its periphery, to adapt it to accentuate the pressure upon the opposite side portions of the shank to assist in producing a "close edge" effect. It will be understood, however, that if desired a tool or roll of a different shape may be utilized, for example such as to adapt it to be used upon

both the forepart and the shank portions of the shoe bottom.

After the bottom of a shoe has been subjected to repeated pressure impulses or blows as above described, it is usually desirable to supplement this operation by the use of rolling pressure, in order further to insure that the sole will present a smooth and even appearance. In accordance with a further feature of the invention, the machine herein shown is accordingly so constructed as to adapt the leveling roll to be used in both these different ways. For the purpose in view, there is provided means for controlling the reciprocatory movements of the roll in such manner as to bring the roll to a stop in pressure-applying relation to the shoe, whereupon the shoe may be subjected to rolling pressure by movement of the jack relatively to the roll. It will be evident that, with this means of control, the machine may, if desired, be used only to apply rolling pressure to a shoe. In order to permit the removal of the shoe, the machine is also adapted to bring the roll to a stop at the limit of its movement away from the shoe bottom, the controlling means being so constructed as to insure that it will come to a stop only at one or the other of its limits of movement toward and from the shoe bottom while enabling the operator to cause it to come to a stop selectively in either of these positions.

In accordance with a further feature of the invention, there is provided a support for the leveling tool or roll so mounted as to permit it to turn about an axis extending heightwise of the shoe, the construction shown including also spring means for normally centralizing the tool with respect to such turning movement. In operating immediately at the rear of the ball-line of the shoe the tool is thus permitted to adjust itself to the lateral contour of the shoe bottom with its axis in substantially parallel relation to the ball-line, while in operating on other portions of the shoe it is maintained in the position best adapted for use thereon.

Another feature of the invention comprises novel means for controlling the movements of the shoe support or jack. As herein illustrated, a single manual means is provided for controlling the power means whereby the shoe support is moved in directions lengthwise of the shoe and for also tipping the shoe laterally at the will of the operator, the construction shown comprising for this purpose a controlling device carried by the shoe support and provided with a pair of handles whereby the operator is enabled to use both hands to control the different movements. By the use of such means the control of the shoe to present it at different times in the desired relation to the leveling tool is greatly facilitated.

For controlling the reciprocatory move-

ments of the leveling tool, the machine is provided with a manually operated clutch-controlling member or treadle which is moved in one direction to start the tool in operation and in the opposite direction to bring it to a stop. In order to relieve the operator of the necessity of holding this member in the starting position until it is desired to bring the tool to a stop, there is further provided a device adapted to be utilized if desired to hold the member in starting position, the construction shown comprising a lock for the treadle with means enabling the operator to unlock or release it at will.

The above and other features of the invention, including various novel details of construction and combinations of parts, will now be more particularly described by reference to the accompanying drawings and pointed out in the claims.

In the drawings,

Fig. 12 is a sectional view illustrating more fully the construction of a portion of the shoe support.

The shoe support or jack is in many respects similar to the construction disclosed in United States Letters Patent No. 1,004,155, granted on September 26, 1911, upon an application of A. Eppler. It comprises a casting 13 pivotally mounted at 14 on the frame 16 of the machine for swinging movements lengthwise of a shoe on the jack, this casting having upwardly extending front and

rear arms 18 and 20 between which there is suspended on pivot studs 22 and 24 a shoe holder 26 having thereon means for supporting a shoe and its last, the supporting means comprising a last pin 28 and a toe rest 30. The last pin 28 is supported on a tipping block 32 which is pivoted at 34 (Fig. 12) on a heel post 36. In the construction herein shown the tipping block 32 is engaged by a spring plunger 38 which tends to swing the last pin in a direction away from the toe rest 30, and manually operated means is provided for swinging the last pin in the opposite direction to clamp the shoe firmly down upon the toe rest. This means comprises a hand lever 40 mounted on a shaft 42 which is rotatable in the heel post 36, this shaft having fast thereon a spiral gear 44 engaging a spiral gear 46 which is internally threaded for engagement with threads on a vertically movable rod 48. The upper end of the rod 48 is in contact with a vertically movable plunger 49 bearing on the tipping block 32 at the opposite side of its axis from the spring plunger 38. Through these connections the tipping block is operated to clamp the shoe on the toe rest after the shoe has been mounted on the last pin 28. The hand lever 40 is so mounted that it may be moved lengthwise of the shaft 42 against the resistance of a spring 50 (Fig. 5) in its hub portion and may then be turned to bring a pin 52 thereon into position to enter any one of a series of holes 54 formed in a flange 55 fast on the shaft 42, so that the lever may be connected to the shaft in different positions. It will be understood that the spiral gears 44, 46 automatically maintain the parts in any position to which they are moved in jacketing a shoe.

The toe rest 30 is adjustable along a guide-way formed on a lever arm 56 which is pivoted at 58 on the shoe holder 26, the adjustment being effected by rack and pinion mechanism controlled by a hand-wheel 60. Adjustment of the toe rest heightwise of the shoe is effected by swinging the lever arm 56 about its pivot 58 through connections including a hand-wheel 62 (Fig. 2) in the same general manner as illustrated in the above-mentioned Letters Patent.

In the use of the machine the shoe support as a whole is swung about its pivot 14, to carry the shoe forwardly and rearwardly at the will of the operator, by power-operated means generally similar to that disclosed in the above-mentioned Letters Patent, while at the same time the shoe holder 26 may be tipped to incline the shoe laterally as desired. The means whereby these movements are effected, including the novel mechanism provided for controlling the power-effected movements of the shoe support and for tipping the shoe holder, will be more particularly hereinafter described.

For leveling the sole of the shoe there is provided a leveling tool or roll 64 which, as herein shown, is particularly adapted to operate upon the shank portion of the sole and is so formed that it has a substantially V-shaped peripheral recess extending around it, as illustrated in Figs. 7 and 8. This roll is mounted to turn and also to slide freely lengthwise of its axis on a rod 66 (Fig. 7) supported on a holder 68 which has fast therein an upwardly extending shaft 70 mounted for turning movement in a bearing formed in the front end of a roll-carrying arm 72 pivoted at 74 on the frame of the machine for swinging movements in a vertical plane about a horizontal axis located at a substantial distance beyond the toe end of the shoe. The shaft 70 is confined in its bearing by a nut 76, and between the holder 68 and the lower face of the arm 72 there is a ball-thrust bearing 78 (Fig. 7). The roll 64 is thus permitted to turn about an axis extending heightwise of the shoe, so that in operating in that portion of the shank immediately at the rear of the ball-line it may adjust itself, in response to engagement of the shoe therewith, to a position in which its axis is substantially parallel to the ball-line for better conformity to the contour of the last in that location. There is further provided means for normally centralizing the roll with respect to turning movement about the axis of the shaft 70, comprising an arm 80 (Fig. 6) which is keyed to the shaft 70 and a spring 82 connected at one end to this arm and connected at its other end to a screw 84 which is clamped in a projection 86 on the arm 72 and is adjustable to vary the tension of the spring.

For imparting to the leveling roll reciprocatory movements heightwise of the shoe there is provided a lever 88 (Figs. 1, 2 and 3) mounted to swing about a rod 90 on the frame of the machine and carrying a roll 92 (Fig. 3) which is engaged by a path cam 94 formed in one side of a cam wheel 96 fast on a cam shaft 98. Pivoted on a pin 100 on the lever 88 is a block 102 connected by pins 103 to the lower end of a sleeve member 104 the upper end of which is connected to a plunger 106 (Fig. 2) slidably movable on a rod 108. Between the plunger 106 and a collar 110 fast on the lower end of the rod 108 is a spring 112. The upper end of the rod 108 is secured between two clamp members 114 and 116 which have opposed threaded recesses for engaging screw threads on the rod and are held in clamping position by tap screws 118. The clamp member 116 is pivotally connected at 120 to an ear 122 which is secured on the roll-carrying arm 72. It will be understood that through these connections the arm 72 is oscillated about the axis of its pivot 74, and that when the leveling roll is carried into engagement with the shoe by downward movement of the arm, the

spring 112 will yield in response to continued downward movement of the operating lever 88. Nuts 124 on the rod 108 are arranged to determine and to vary the initial compression of the spring 112 by engagement with the plunger 106 and thus to determine the amount of pressure applied to the shoe by the roll. Since adjustment of these nuts has the effect of moving the rod 108 and, therefore, of varying the position of the roll heightwise of the shoe, there is provision for a compensating adjustment by loosening the clamp members 114, 116 and changing their position lengthwise of the rod 108.

15 The cam shaft 98 is operated through a clutch under such control that the operator may start and stop the reciprocatory movements of the leveling roll at will. In the machine herein shown power is derived from 20 an electric motor 126 (Fig. 2) which by means of a pinion 128 on the motor shaft and an idle pinion 130 drives a gear wheel 132 loosely mounted on the shaft 98. The gear wheel 132 (Fig. 3) has on one side an inter- 25 nal friction clutch surface 134 to adapt it to serve as a clutch member, and for engaging this clutch surface there is provided a co-operating friction clutch member 136 which is mounted for sliding movement lengthwise 30 of the shaft 98 and is connected to the shaft by a spline 138. The clutch member 136 is moved lengthwise of the shaft 98 by a yoke member 140 fast on a rock shaft 142 which is mounted on the frame of the machine and 35 is provided with an arm 144 the outer end of which is pivotally connected to a sleeve member 146 slidably movable on a rod 148. The rod 148 has fast thereon a collar 150 arranged to engage the upper end of the member 146 and thus to impart swinging movement 40 to the arm 144 to release the clutch in response to downward movement of the rod 148. This rod is connected at its lower end to a treadle 152 pivoted at 154 on a bracket 45 156 secured to the frame of the machine. Between the lower end of the sleeve member 146 and a member 158 which serves as a connection between the rod 148 and the treadle is a spring 160 through which movement is 50 imparted yieldingly to the arm 144 to set the clutch in response to upward movement of the member 158 when the treadle is depressed. A spring 162 is connected to the treadle to hold it normally in its idle position and to 55 release the clutch by returning it to that position.

Co-operating with the clutch is a brake for immediately stopping the reciprocatory movements of the leveling roll when the 60 clutch is released. This brake comprises a band 164 arranged to act frictionally on the periphery of the cam wheel 98. The opposite ends of the band are connected respectively to different arms of a bell-crank 166 mounted on a rock shaft 168, and secured also

on this rock shaft are a pair of lever arms 170 to which a spring 172 is connected to assist in contracting the band 164 and thus applying the brake. For releasing the brake simultaneously with the setting of the clutch in the upward movement of the treadle-operated rod 148, this rod is extended upwardly and has mounted on its upper end a block 174 pivotally mounted between the two arms 170. It will be understood that when the clutch is released by downward movement of the rod 148, the spring 172 is permitted to act to apply the brake, this spring supplementing the action of the treadle spring 162.

It will be understood from the foregoing description that the reciprocatory movements of the leveling roll are started when the operator depresses the treadle 152 and that these movements will continue as long as the treadle is held in its depressed position. In order to relieve the operator of the necessity of holding the treadle depressed when it is desired that the beating movements of the roll shall continue for a considerable length of time, there is provided automatic means for locking the treadle in its depressed position. By reference to Figs. 4 and 4a, it will be seen that there is mounted for vertical movement in a bracket 176 on the front end of the frame of the machine a plunger 178 which is adjustably connected by means of a threaded rod 180 and a pin 182 to a member 184 secured to the treadle 152. Mounted for movement in a bearing in the bracket 176 in directions at right angles to the directions of movement of the plunger 178 is a locking pin 186 which is arranged to be projected over the top end face of the plunger 178 when the plunger is moved far enough downwardly by depression of the treadle. The pin 186 is connected to an arm 188 fast on a rock shaft 190 to which is also connected a lever arm 192. At its lower end the arm 192 is connected to a treadle 194 which is pivoted on an arm 196 of the bracket 176. A spring 198 acts on the arm 192 to slide the locking pin 186 over the top of the plunger 178 when the plunger is depressed far enough to permit this movement, and thus to hold the clutch members 132, 136 in operative engagement with each other. When it is desired to stop the beating movements of the leveling roll, the operator depresses the treadle 194 and thereby withdraws the pin 186 from over the top of the plunger 178, whereupon the spring 162 raises the treadle 152 and thereby releases the clutch and applies the brake.

After the leveling roll has been utilized to beat the sole, and thus on turn work to flatten the seam and substantially conform the sole to the transverse curvature of the last in the shank, it is usually desirable to complete the shaping or leveling operation by rolling pressure in order to insure that the sole will present a smooth and even appearance. To 133

permit the use of the roll for this purpose it is necessary to bring it to a stop in a position in which it is in engagement with the sole. On the other hand, after the leveling operation has been completed the roll should be positioned at a substantial distance above the shoe to permit the shoe to be carried from under the roll by the movement of the jack. There is, accordingly, further provided additional controlling means so constructed as to cause the roll to come to a stop either at one or the other of its limits of movement toward and from the shoe. To this end, there is secured to the cam shaft 98 a cam 200 (Fig. 3) having diametrically opposite raised portions arranged to engage a roll 202 mounted on a bracket 204 which is secured to the treadle-operated rod 148. It will be evident that when either of the opposite raised portions of the cam 200 is in engagement with the roll 202, the rod 148 is necessarily held in such a position that the clutch is set and the brake released. On the other hand, when either of the raised portions of the cam passes beyond the roll 202, the rod 148 is permitted to move downwardly and thus to release the clutch and apply the brake if the treadle 152 has been released so as to permit this action to occur. If it should happen that the leveling roll is thus brought to a stop in engagement with the shoe when it is desired that it be stopped at its opposite limit of movement, or vice versa, all that the operator has to do is to depress the treadle 152 momentarily to cause the cam 200 to turn half way around, whereupon the roll will be brought to a stop in the position desired.

The power-operated means for imparting to the shoe support or jack movements in directions lengthwise of the shoe is of substantially the same construction as that disclosed in Letters Patent No. 1,004,155, hereinbefore referred to. This means comprises a leather-faced friction drum 206 (Fig. 1) connected with the jack by mechanism hereinafter described and arranged to be engaged on its periphery at diametrically opposite points by two friction pulleys 208 and 210 which are driven constantly in opposite directions and which are so mounted that either pulley can be moved into engagement with the drum 206. The pulleys 208 and 210 are driven by means of a belt 212 passing over pulleys 214 and 216 secured to the shafts of the pulleys 208 and 210 respectively, and also passing over an idle pulley 218 and over a pulley 220 secured to a driving shaft 222. The shaft 222 carries a pinion 224 (Fig. 2) engaged by the constantly driven gear wheel 132.

To permit the driving pulleys 208 and 210 to be moved selectively into engagement with the drum 206, these driving pulleys, together with the pulleys 214, 216 and 218, are mounted on a frame 226 which is pivotally supported on the driving shaft 222. By swinging

movement of this frame either of the driving pulleys 208 and 210 can be carried into engagement with the drum 206 without altering the tension of the belt 212.

The connections between the above-described reversible friction mechanism and the jack comprise a pinion 228 mounted to rotate with the drum 206, a gear wheel 230 engaged by the pinion 228, a crank shaft 232 (Fig. 2) to which the gear wheel 230 is secured, and a link 234 connecting a crank pin 236 carried by this shaft to the swinging jack member 13. It will thus be understood that rotation of the drum 206 alternately in opposite directions oscillates the shaft 232 and through the link 234 oscillates the jack about the axis of its pivot 14 to carry the shoe on the jack forwardly and rearwardly under the leveling roll.

The invention provides novel means for controlling the above-described reversible friction driving mechanism and for also tipping the shoe holder 26 about the axis of its pivots 22 and 24 through the use of a single manually operated device arranged to perform both these functions. Secured to a rock shaft 238 (Figs. 1 and 5) carried by the jack member 13 is an arm 240 connected by a link 242 to the rocking frame 226, and also fast on the rock shaft is an arm 244 extending upwardly and connected by a link 246 to a substantially U-shaped member 248 which is slidable lengthwise of a shaft 250 mounted to turn in a bearing in the arm 18 of the jack. Fast on the shaft 250 is a depending arm 252 provided with a slot 254 in which is mounted a roll 256 carried by the adjacent upwardly extending arm of the shoe holder 26. It will thus be seen that by turning movement of the shaft 250 the shoe holder 26 may be tipped to one side or the other. Secured to the shaft 250 is a sleeve member 258 along which the member 248 may slide, and between the opposite ends of this sleeve member there is provided a square portion 260 (Figs. 10 and 11) on which is slidably mounted a block 262 positioned between the opposite arms of the member 248. Mounted in the opposite sides of the block 262 are handles 264 which the operator holds with his two hands. It will thus be understood that by the use of the handles 264 the block 262 may be operated to turn the shaft 250 and its sleeve 258 and thereby to tip the shoe holder 26 in either direction desired in any position of the block 262 lengthwise of the shaft 250. By the use of the same handles the operator is enabled to move the member 248 either forwardly or rearwardly lengthwise of the shaft 250 and the sleeve 258 and thereby to operate the arm 244 in such manner as to connect either of the friction pulleys 208, 210 to the drum 206 connected to the jack, thus causing the jack to be swung in either direction desired. It will be seen that in every instance the move-

ment of the jack thus effected by the friction driving mechanism is in the same direction as the movement of the controlling member 248.

To guard against any overthrow of the 5 jack, the machine is provided with means of substantially the same construction as shown in Letters Patent No. 1,004,155 for throwing the friction driving mechanism out of operation at a predetermined limit of swinging 10 movement of the jack in either direction, by automatically moving the frame 226 in a direction to disengage from the drum 206 that one of the driving pulleys 208, 210 which is in operation. This means comprises two 15 rolls 266 and 268 (Fig. 1) adjustably secured to the gear wheel 230 and arranged to engage an arm 270 projecting from a sleeve 272 which is mounted to turn on the shaft 14 about which the jack member 13 swings, the sleeve 20 272 being connected to the frame 226 by yielding means comprising links 274 and 276 and springs 278 (Fig. 2), the construction of which need not be described in detail in view of the disclosure in the above-mentioned Letters Patent. When the jack arrives at a 25 predetermined point in its movement in either direction, one of the rolls 266, 268 engages the arm 270 and through the yielding connections provided moves the frame 226 in the direction 30 to disconnect the jack from the driving means.

As also illustrated in the above-mentioned Letters Patent, the machine is provided with means for steadyng the jack in its swinging 35 movements and for stopping its movement when it is disconnected from the driving mechanism, comprising a brake member 280 (Fig. 2) arranged to press continuously on a brake disk 282 carried by the shaft 232. The 40 brake member 280 is mounted on a pivoted lever 284 and is pressed against the disk 282 by a spring 286 which acts on the lever 284.

The frame 226 of the reversible jack driving mechanism is further controlled by a device of substantially the same construction as 45 that disclosed in United States Letters Patent No. 996,707, granted on July 4, 1911, upon an application of A. Eppler, which serves to maintain the frame yieldingly in a predetermined 50 position when the handles 264 are released by the operator. This device comprises a rod 288 (Fig. 1) pivotally connected to the frame 226 and extending through an eye-bolt 290 on the frame of the machine, 55 with springs 292 and 294 at opposite sides of the eye-bolt arranged to act on the rod with a tendency to maintain the frame in a predetermined position and against the resistance of one or the other of which the frame 60 is swung by the operator by means of the handles 264. These springs are adjustable by means of nuts on the rod 288 to vary the tension of either of them independently of the other, and by such adjustment the frame 65 226 may be held normally in a position in

which both the driving pulleys 208 and 210 are out of engagement with the drum 206. Preferably, however, the device will be so adjusted as to tend to hold the pulley 210 lightly in engagement with the drum 206 so as to cause the jack to be swung outwardly to its idle position whenever the handles 264 are released by the operator. It will be further evident that the springs 292 and 294 tend to counterbalance the frame 226 so that it may be more easily moved by the operator in one direction or the other. This counterbalancing means also serves to facilitate the manual control of the frame when it is desired to suspend the swinging movement of the jack in order to subject some particular part of the sole to repeated action of the leveling tool.

In the operation of the machine, briefly summarized, the operator mounts a shoe on the jack pin 28 when the jack is in its normal idle position and by movement of the handle 40 tips the jack pin to clamp the shoe firmly upon the toe rest 30. He then grasps the handles 264 and by pushing forwardly thereon connects the jack to the reversible friction driving mechanism to cause it to carry the shoe forwardly under the leveling roll 64 which is at that time held at its upper limit of movement. When the jack arrives in a position in which the roll is over the shank portion of the sole, the operator depresses the treadle 152 to set the clutch and release the brake and thereby cause the roll to be carried repeatedly into and out of engagement with the shoe by the action of the cam 94 to subject the sole to a plurality of blows. Since the roll 64 as illustrated is intended to operate only on the shank portion of the sole, the operator will control the movements of the jack by manipulation of the handles 264 in such manner as to cause this portion only of the sole to be moved forwardly and rearwardly under the roll as many times as desired. At the same time, by further manipulation of the handles 264, the operator will tip the shoe holder 26 in opposite directions as desired to cause the beating action of the roll to be accentuated upon the opposite edge portions of the sole and thereby to impart to the sole the desired transverse curvature with its edges pressed closely against the upper. It will be understood that while thus controlling the lateral inclination of the shoe, the operator may at any time stop the swinging movements of the jack to cause any particular portion of the sole to receive repeated blows from the leveling roll. At any time in the action of the roll on the shoe, and particularly when it is acting upon that portion of the sole immediately at the rear of the ball-line, the roll may turn about the axis of the shaft 70 against the resistance of the

spring 82 to adjust itself to the transverse contour of the last bottom.

In operating as above described, the operator may hold his foot upon the treadle 152 until it is desired to terminate the beating action of the roll, or alternatively he may depress the treadle far enough to cause it to be locked by the pin 186. If the treadle is thus locked, the beating action of the roll will be continued until the operator depresses the treadle 194 to unlock the treadle 152. When the treadle 152 is permitted to rise in response to the action of its spring 162, the clutch is released and the brake applied in the manner hereinbefore described. By reason of the action of the cam 200 the roll can come to a stop only at its upper limit of movement or at its lower limit of movement. It is usually desirable that, after the beating action of the roll upon the sole, the latter shall be subjected to rolling pressure in order to smooth it and thereby complete the leveling action. To permit that operation the roll should be brought to a stop at its lower limit of movement, and if it should happen that when the treadle 152 is released the roll does not come to a stop in that position, it may be returned to that position in response to a momentary depression of the treadle. While the roll carrier 72 is then held stationary, the operator will cause the jack to be swung back and forth by the friction driving mechanism so that the sole will receive rolling pressure, the roll at that time being held against the shoe by the compression of the spring 112. During such rolling action the operator will further tip the shoe holder as desired. When the leveling operation has been completed, the operator will again momentarily depress the treadle 152 far enough to cause the clutch to act, but not far enough to cause the treadle to be locked, whereupon the cam 200 will be turned far enough to cause the roll to be brought to a stop at its upper limit of movement. The jack-controlling mechanism will then be manipulated to cause the jack to be swung outwardly to its idle position, or if the operator merely releases the handles 264, the jack will thus be returned automatically in response to the controlling action of the springs 292, 294 on the frame 226.

Having described the invention, what I claim as new and desire to secure by Letters Patent of the United States is:—

1. A machine of the class described having, in combination, a shoe support, a leveling roll so mounted as to permit it to turn in response to engagement with a shoe on the shoe support, and power-operated means for imparting to said leveling roll a plurality of reciprocatory movements heightwise of the shoe into and out of engagement with the bottom of the shoe to deliver repeated blows upon the shoe bottom.

2. A machine of the class described having, in combination, a shoe support and a leveling roll relatively movable in directions lengthwise of a shoe on the support, said roll being so mounted as to permit it to turn in response to engagement of the shoe therewith, a roll support mounted for swinging movements heightwise of the shoe about an axis located beyond an end of the shoe, and automatic means for imparting to said roll support continuously in operating upon a portion of the bottom of the shoe swinging movements to carry the roll into and out of engagement with the shoe bottom and thereby cause the roll to deliver a plurality of blows upon the shoe bottom.

3. A machine of the class described having, in combination, a shoe support and a leveling tool relatively movable in directions lengthwise of a shoe on the support, an arm supporting said leveling tool and mounted for swinging movements heightwise of the shoe in a plane extending lengthwise of the shoe to carry the tool into and out of engagement with the bottom of the shoe, and power-operated mechanism connected to said arm for swinging it repeatedly about its axis in operating upon a portion of the bottom of the shoe to cause the tool to deliver a plurality of blows upon that portion of the shoe bottom.

4. A machine of the class described having, in combination, a shoe support and a leveling tool relatively movable in directions lengthwise of a shoe on the support, an arm supporting said leveling tool and mounted for swinging movements heightwise of the shoe to carry the tool into and out of engagement with the bottom of the shoe, power-operated mechanism connected to said arm for swinging it repeatedly about its axis to cause the tool to deliver a plurality of blows upon the shoe bottom, and controlling means constructed to enable the operator to start the operation of said arm and stop its operation at will.

5. A machine of the class described having, in combination, a shoe support and a leveling tool relatively movable in directions lengthwise of a shoe on said support, an arm supporting said tool at one end and pivotally mounted at its other end for swinging movements heightwise of the shoe to carry the tool into and out of engagement with the bottom of the shoe, and clutch-controlled cam mechanism including a longitudinally movable rod connected to said arm between its ends for swinging it repeatedly about its axis in operating upon a portion of the bottom of the shoe to cause the tool to deliver a plurality of blows upon that portion of the shoe bottom.

6. A machine of the class described having, in combination, a shoe support and a leveling roll relatively movable in directions lengthwise of a shoe on the support, said roll being

mounted for turning movement in response to engagement of the shoe therewith, an arm supporting said roll and mounted for swinging movements heightwise of the shoe to carry the roll into and out of engagement with the bottom of the shoe, and power-operated mechanism connected to said arm in a location between the roll and the axis of the arm for swinging the arm repeatedly about its axis in operating upon a portion of the bottom of the shoe to cause the roll to deliver a plurality of blows upon that portion of the shoe bottom.

7. A machine of the class described having, in combination, a shoe support and a leveling roll relatively movable in directions lengthwise of a shoe on the support to cause the roll to traverse the shank portion of the shoe, said roll being mounted for turning movement in response to engagement of the shoe therewith, and automatic means for imparting to said leveling roll in operating upon the shank portion of the shoe a plurality of reciprocatory movements heightwise of the shoe into and out of engagement with the bottom of the shoe to deliver a plurality of blows upon the shoe bottom.

8. A machine of the class described having, in combination, a shoe support and a leveling roll relatively movable in directions lengthwise of a shoe on the support, said roll being so mounted as to permit it to turn in response to engagement of the shoe therewith, automatic means for imparting to said leveling roll reciprocatory movements heightwise of the shoe into and out of engagement with the bottom of the shoe to deliver a plurality of blows upon the shoe bottom, and controlling means constructed to enable the operator to vary at will the number of blows delivered upon selected portions of the shoe bottom.

9. A machine of the class described having, in combination, a shoe support and a leveling tool relatively movable in directions lengthwise of a shoe on the support, power means for operating said tool to apply to the bottom of the shoe repeated pressure impulses in a direction heightwise of the shoe, and controlling means constructed to enable the operator to start or stop at will the power operation of the tool independently of the relative movement of the shoe support and the tool lengthwise of the shoe.

10. A machine of the class described having, in combination, a shoe support and a leveling roll relatively movable in directions lengthwise of a shoe on the support, said roll being so mounted as to permit it to turn in response to engagement of the shoe therewith, power means for operating the roll to apply to the bottom of the shoe repeated pressure impulses in a direction heightwise of the shoe, and controlling means constructed to enable the operator to start or stop at will the power operation of the roll independ-

ently of the relative movement of the shoe support and the roll lengthwise of the shoe.

11. A machine of the class described having, in combination, a shoe support and a leveling roll relatively movable in directions lengthwise of a shoe on the support, said roll being so mounted as to permit it to turn in response to engagement of the shoe therewith, power-operated means comprising a cam for imparting to the roll reciprocatory movements heightwise of the shoe into and out of engagement with the bottom of the shoe to deliver a plurality of blows upon the shoe bottom, and means for controlling said cam to start or stop at will the reciprocatory movements of the roll independently of the relative movement of the shoe support and the roll lengthwise of the shoe.

12. A machine of the class described having, in combination, a shoe support and a leveling roll relatively movable in directions lengthwise of a shoe on the support to cause the roll to traverse the shank portion of the shoe bottom, said roll being mounted for turning movement in response to engagement of the shoe therewith and having a recess extending about its periphery so formed as to cause the roll to accentuate the pressure on the opposite side portions of the sole, and automatic means for operating said roll to apply repeated pressure impulses to the shank portion of the sole.

13. A machine of the class described having, in combination, a shoe support and a leveling roll relatively movable in directions lengthwise of a shoe on the support to cause the roll to traverse the shank portion of the shoe bottom, said roll being mounted for turning movement in response to engagement of the shoe therewith and having a substantially V-shaped recess extending about its periphery to accentuate the pressure on the opposite side portions of the sole.

14. A machine of the class described having, in combination, a shoe support and a leveling roll relatively movable in directions lengthwise of a shoe on the support to cause the roll to traverse the shank portion of the shoe bottom, said roll being mounted for turning movement in response to engagement of the shoe therewith and having a substantially V-shaped recess extending about its periphery to accentuate the pressure on the opposite side portions of the sole, a support for said roll, and power-operated means for imparting to said roll support a plurality of reciprocatory movements heightwise of the shoe to carry the roll into and out of engagement with the bottom of the shoe and thereby cause it to deliver a plurality of blows upon the shoe bottom.

15. A machine of the class described having, in combination, a shoe support and a leveling tool relatively movable in directions lengthwise of a shoe on the support, said shoe

- support being constructed to enable the operator to tip the shoe laterally at will, and power-operated means for imparting to said leveling tool reciprocatory movements to deliver repeated blows upon the bottom of the shoe. 5
16. A machine of the class described having, in combination, a shoe support and a leveling tool relatively movable in directions lengthwise of a shoe on the support, manually operated means for tipping the shoe laterally in the leveling operation to a variable extent as determined by the operator, and power-operated means for imparting to said leveling tool reciprocatory movements heightwise of the shoe into and out of engagement with the bottom of the shoe to deliver repeated blows upon the shoe bottom. 10
17. A machine of the class described having, in combination, a shoe support and a leveling tool relatively movable in directions lengthwise of a shoe on the support, means constructed to enable the operator at will to effect a relative tipping movement of said tool and the shoe laterally of the shoe, and power-operated means for imparting to said leveling tool reciprocatory movements heightwise of the shoe into and out of engagement with the bottom of the shoe to deliver repeated blows upon the shoe bottom. 15
18. A machine of the class described having in combination, a shoe support and a leveling roll relatively movable in directions lengthwise of a shoe on the support, said roll being so mounted as to permit it to turn in response to engagement of the shoe therewith, power-operated means for imparting to said roll reciprocatory movements heightwise of the shoe into and out of engagement with the bottom of the shoe to deliver repeated blows upon the shoe bottom, and means for tipping the shoe laterally during the reciprocatory movements of the roll. 20
19. A machine of the class described having, in combination, a shoe support and a leveling roll relatively movable in directions lengthwise of a shoe on the support to cause the roll to traverse the shank portion of the shoe, said roll having a substantially V-shaped recess extending about its periphery, power-operated means for operating said roll to apply to the bottom of the shoe repeated pressure impulses in directions heightwise of the shoe, and manual means to enable the operator to tip the shoe laterally at will during the operation of the roll thereon. 25
20. A machine of the class described having, in combination, a shoe support movable in directions lengthwise of a shoe thereon, a leveling roll so mounted as to permit it to turn in response to engagement of the shoe therewith, and power-operated means for imparting to said roll continuously in its action upon a portion of the bottom of the shoe reciprocatory movements heightwise of the shoe into and out of engagement with the shoe to deliver repeated blows upon the shoe bottom. 30
21. A machine of the class described having, in combination, a shoe support movable in directions lengthwise of a shoe thereon, a leveling tool, power-operated mechanisms arranged respectively to operate the shoe support and to operate the leveling tool to apply repeated pressure impulses to the shoe bottom, and means constructed to enable the operator in the operation of the machine on each shoe to start or stop each of said power-operated mechanisms at will independently of the other. 35
22. A machine of the class described having, in combination, a shoe support movable in directions lengthwise of a shoe thereon, power-operated means for thus moving said shoe support constructed to enable the operator to start or stop the movement at will, a leveling tool, power-operated means for imparting to said leveling tool during the movement of the shoe support reciprocatory movements heightwise of the shoe into and out of engagement with the bottom of the shoe to deliver repeated blows upon the shoe bottom, and means for starting or stopping the power operation of the leveling tool independently of the movements of the shoe support. 40
23. A machine of the class described having, in combination, a shoe support movable in directions lengthwise of a shoe thereon, manually controlled clutch means for thus moving said shoe support and for starting, stopping or reversing the movement at will, a leveling tool, and separate manually controlled clutch means for operating said leveling tool to apply repeated pressure impulses upon the bottom of the shoe and for starting or stopping at will the operation of the tool. 45
24. A machine of the class described having, in combination, a shoe support movable in directions lengthwise of a shoe thereon, power-operated means for thus moving said shoe support, a leveling roll, power-operated means for imparting to said leveling roll during the movement of the shoe support reciprocatory movements heightwise of the shoe into and out of engagement with the bottom of the shoe to deliver a plurality of blows upon the shoe bottom, and manually operated means for starting or stopping the movements of the roll independently of the movements of the shoe support. 50
25. A machine of the class described having, in combination, a shoe support movable in directions lengthwise of a shoe thereon, power-operated means for thus moving said shoe support constructed to enable the operator to start or stop the movement at will, a leveling roll, power-operated means for imparting to said leveling roll reciprocatory 55

movements heightwise of the shoe into and out of engagement with the bottom of the shoe to deliver a plurality of blows upon the shoe bottom, and means for starting or stopping said movements of the roll at will independently of the movements of the shoe support.

26. A machine of the class described having, in combination, a shoe support, manually controlled power-operated means for moving said shoe support in directions lengthwise of a shoe thereon, manual means for tipping the shoe laterally at the will of the operator as the shoe support is thus moved, a leveling tool, and means for imparting to said tool during the movement of the shoe support reciprocatory movements heightwise of the shoe to deliver repeated blows upon the bottom of the shoe.

27. A machine of the class described having, in combination, a shoe support, manually controlled power-operated means for moving said shoe support in directions lengthwise of a shoe thereon, manual means for tipping the shoe laterally at the will of the operator as the shoe support is thus moved, a leveling roll, and power-operated means arranged to be controlled independently of the shoe support for imparting to said roll reciprocatory movements heightwise of the shoe to deliver a plurality of blows upon the bottom of the shoe.

28. A machine of the class described having, in combination, a shoe support and a leveling tool relatively movable in directions lengthwise of a shoe on the support, said shoe support being constructed to tip the shoe laterally, power-operated means for effecting the relative movement of the shoe support and the tool lengthwise of the shoe, a single manually operated mechanism for controlling said power means and for also enabling the operator to tip the shoe at will, and power means for operating the tool to deliver repeated blows upon the bottom of the shoe.

29. A machine of the class described having, in combination, a shoe support movable in directions lengthwise of a shoe thereon and constructed to tip the shoe laterally, power-operated means for moving the shoe support lengthwise of the shoe, a single manually operated mechanism for controlling said power means and for also enabling the operator to tip the shoe at will, a leveling tool, and power means for operating said leveling tool to apply repeated pressure impulses to the bottom of the shoe.

30. A machine of the class described having, in combination, a shoe support movable in directions lengthwise of a shoe thereon and constructed to tip the shoe laterally, power-operated means for moving the shoe support lengthwise of the shoe, a single manually operated mechanism for controlling said power

means and for also enabling the operator to tip the shoe at will, a leveling roll so mounted as to permit it to turn in response to engagement of the shoe therewith, and power-operated means for operating said leveling roll to apply repeated pressure impulses to the bottom of the shoe in directions heightwise of the shoe.

31. A machine of the class described having, in combination, a shoe support movable in directions lengthwise of a shoe thereon and constructed to tip the shoe laterally, power-operated means for moving the shoe support lengthwise of the shoe, a single manually operated mechanism for controlling said power means and for also enabling the operator to tip the shoe at will, a leveling roll mounted to turn in response to engagement of the shoe therewith, a roll support, and power-operated means for imparting to said roll support reciprocatory movements heightwise of the shoe to carry the roll into and out of engagement with the bottom of the shoe and thereby deliver a plurality of blows upon the shoe bottom.

32. In a machine of the class described, a shoe support and a leveling tool relatively movable in directions lengthwise of a shoe on the support, power-operated means for effecting such relative movement, said shoe support being constructed to tip the shoe laterally, and a single manually operated device for controlling said power-operated means and for also tipping the shoe.

33. In a machine of the class described, a shoe support and a leveling tool relatively movable in directions lengthwise of a shoe on the support, power-operated means for effecting such relative movement, said shoe support being constructed to tip the shoe laterally, a manually operated member enabling the operator thus to tip the shoe at will, and means arranged to be operated by the same member to control the relative movement of the shoe support and the tool lengthwise of the shoe.

34. In a machine of the class described, the combination with a leveling tool, of a shoe support movable relatively to said tool in directions lengthwise of a shoe thereon, power-operated means for thus moving the shoe support, said shoe support including a shoe holder mounted for tipping movement to incline the shoe laterally, and a single manually operated device for controlling said power-operated means and for also tipping said holder.

35. In a machine of the class described, the combination with a leveling roll, of a shoe support movable relatively to said roll in directions lengthwise of a shoe thereon, power-operated means for thus moving the shoe support, said shoe support being constructed to tip the shoe laterally, a manually operated member for thus tipping the shoe,

and means arranged to be operated by the same member to control the movement of the shoe support lengthwise of the shoe.

36. In a machine of the class described, the combination with a leveling tool, of a shoe support movable relatively to said tool in directions lengthwise of a shoe thereon, power-operated driving means for thus moving said shoe support at the will of the operator, the shoe support including a shoe holder mounted for tipping movement to incline the shoe laterally, and a manually operated member carried by said shoe support for controlling said driving means and for also tipping said holder.

37. In a machine of the class described, the combination with a leveling tool, of a shoe support movable relatively to said tool in directions lengthwise of a shoe thereon, power-operated means for thus moving the shoe support at the will of the operator, said shoe support including a shoe holder mounted for tipping movement to incline the shoe laterally, a pair of handles connected to said holder for tipping it manually, and connections between said handles and the power-operated means for also controlling the power movements of the shoe support.

38. In a machine of the class described, the combination with a leveling tool, of a shoe support movable relatively to said tool in directions lengthwise of a shoe thereon, power-operated clutch means for moving said shoe support in opposite directions at the will of the operator, said shoe support including a shoe holder mounted for tipping movement to incline the shoe laterally, a manually operated member carried by the shoe support for tipping said holder, and clutch-controlling mechanism connected to said member to cause the shoe support to be moved in a forward direction in response to forward movement of said member and in a rearward direction in response to rearward movement of said member.

39. In a machine of the class described, the combination with a leveling tool, of a shoe support movable relatively to said tool in directions lengthwise of a shoe thereon, power-operated means for thus moving the shoe support, and a manually operated member carried by the shoe support for controlling said power means.

40. In a machine of the class described, the combination with a leveling tool, of a shoe support movable relatively to said tool in directions lengthwise of a shoe thereon, power-operated means for moving the shoe support in opposite directions at the will of the operator, and a manually operated member carried by the shoe support and connected to said power means to cause said support to be moved in a forward direction in response to forward movement of said member

and in a rearward direction in response to rearward movement of said member.

41. A machine of the class described having, in combination, a shoe support, a leveling tool arranged to extend across the bottom of a shoe on said support, said tool being mounted for turning movement about an axis extending heightwise of the shoe to adjust itself to the contour of the shoe bottom, and spring means for normally centralizing the tool with respect to such turning movement.

42. A machine of the class described having, in combination, a shoe support, a leveling roll adapted to operate upon the shank portion of the bottom of a shoe on said support with its axis extending laterally of the shoe, said roll being mounted for turning movement about an axis extending heightwise of the shoe to adjust itself to the contour of that portion of the shank adjacent to the ball of the shoe, and spring means for normally centralizing the roll with respect to such turning movement.

43. A machine of the class described having, in combination, a shoe support, a leveling roll, a roll carrier movable heightwise of a shoe on the support, a roll holder mounted for turning movement on said carrier about an axis extending heightwise of the shoe to permit the roll to adjust itself into substantially parallel relation to the ball-line of the shoe, and a spring connected to said holder for normally centralizing it with respect to such turning movement.

44. A machine of the class described having, in combination, a shoe support and a leveling tool relatively movable in directions lengthwise of a shoe on said support, and means for imparting to said leveling tool during such relative movement a plurality of reciprocatory movements heightwise of the shoe to deliver repeated blows upon the bottom of the shoe, said tool being so mounted as to permit it to turn about an axis extending heightwise of the shoe in response to engagement of a portion of the bottom of the shoe therewith to adjust itself into substantially parallel relation to the ball-line of the shoe.

45. A machine of the class described having, in combination, a shoe support and a leveling roll relatively movable in directions lengthwise of a shoe on said support, means for imparting to said roll reciprocatory movements heightwise of the shoe to deliver repeated blows upon the bottom of the shoe, the roll being mounted for turning movement about an axis extending heightwise of the shoe to adjust itself to the contour of the shoe bottom, and spring means for normally centralizing the roll with respect to such turning movement.

46. A machine of the class described having, in combination, a shoe support, a leveling roll, and means for utilizing said roll at different times to apply rolling pressure to

the bottom of a shoe on the support and to apply to the shoe repeated pressure impulses in the direction of its height.

47. A machine of the class described having, in combination, a shoe support, a leveling roll, and means for utilizing said roll alternatively to apply to the bottom of a shoe on the support either rolling pressure or a plurality of blows.

48. A machine of the class described having, in combination, a shoe support, a leveling roll, and power-operated means for utilizing said roll both to apply rolling pressure to the bottom of a shoe on the support and to apply thereto a plurality of blows.

49. A machine of the class described having, in combination, a shoe support, a leveling roll, means for operating said roll to apply to the bottom of a shoe on the support repeated pressure impulses in the direction of its height, and means for effecting relative movement of the shoe support and the roll lengthwise of the shoe with said first-named means at rest to cause the roll to apply rolling pressure to the shoe.

50. A machine of the class described having, in combination, a shoe support and a leveling roll relatively movable in directions lengthwise of a shoe on the support, and means for imparting to said roll reciprocatory movements heightwise of the shoe to deliver a plurality of blows upon the shoe bottom, said means being constructed to maintain the roll alternatively in position to apply rolling pressure to the bottom of the shoe in response to the relative movement of the shoe support and the roll lengthwise of the shoe.

51. A machine of the class described having, in combination, a shoe support and a leveling roll relatively movable in directions lengthwise of a shoe on the support, power-operated means for imparting to said leveling roll reciprocatory movements heightwise of the shoe into and out of engagement with the bottom of the shoe to deliver a plurality of blows upon the shoe bottom, and means for stopping said reciprocatory movements with the roll in position to be utilized to apply rolling pressure to the bottom of the shoe.

52. A machine of the class described having, in combination, a shoe support and a leveling roll relatively movable in directions lengthwise of a shoe on the support, power-operated means for imparting to said leveling roll reciprocatory movements heightwise of the shoe into and out of engagement with the bottom of the shoe to deliver a plurality of blows upon the shoe bottom, and controlling means constructed to enable the operator to stop said reciprocatory movements at will, said controlling means being constructed to bring the roll to a stop in pressure-applying relation to the bottom of the shoe to permit it to be used to apply rolling pressure to the shoe.

53. A machine of the class described having, in combination, a shoe support, a leveling roll, power-operated means for operating said roll to apply to the bottom of a shoe on the support repeated pressure impulses in the direction of the height of the shoe, controlling mechanism constructed to bring said power means to a stop with the roll in position to apply rolling pressure to the bottom of the shoe, and manually controlled means for imparting to the shoe support movement relatively to the roll in directions lengthwise of the shoe and for stopping such movement at the will of the operator.

54. A machine of the class described having, in combination, a shoe support, a leveling roll, power-operated means for operating said roll to apply to the bottom of a shoe on the support repeated pressure impulses in the direction of the height of the shoe, controlling mechanism constructed to bring said power means to a stop with the roll in position to apply rolling pressure to the bottom of the shoe, power-operated means for imparting to the shoe support movement relatively to the roll in directions lengthwise of the shoe, and mechanism for controlling said power means to start, stop or reverse the movement of the shoe support at the will of the operator.

55. A machine of the class described having, in combination, a shoe support and a leveling roll relatively movable in directions lengthwise of a shoe on the support, power-operated means for effecting such relative movement, power-operated means for imparting to said roll reciprocatory movements heightwise of the shoe to deliver repeated blows upon the shoe bottom, and means for stopping the reciprocatory movements of the roll while continuing the relative movement of the shoe support and the roll lengthwise of the shoe to cause the roll to apply rolling pressure to the bottom of the shoe.

56. A machine of the class described having, in combination, a shoe support and a leveling tool relatively movable in directions lengthwise of a shoe on the support, power-operated means for imparting to said leveling tool reciprocatory movements heightwise of the shoe into and out of engagement with the bottom of the shoe, and controlling mechanism constructed to bring said tool to a stop selectively at the will of the operator either in engagement with the shoe or out of engagement therewith.

57. A machine of the class described having, in combination, a shoe support and a leveling tool relatively movable in directions lengthwise of a shoe on the support, power-operated means for imparting to said leveling tool reciprocatory movements heightwise of the shoe into and out of engagement with the bottom of the shoe, a manually controlled member movable into position to stop the reciprocatory movements of the tool, and a

- device associated with said member to cause the tool to come to a stop only at one or the other of its limits of movement toward and from the shoe as determined by the operator.
58. A machine of the class described having, in combination, a shoe support and a leveling roll relatively movable in directions lengthwise of a shoe on the support, power-operated means for imparting to said leveling roll reciprocatory movements heightwise of the shoe into and out of engagement with the bottom of the shoe, and manually controlled mechanism for stopping said reciprocatory movements of the roll, said mechanism being constructed to bring the roll to a stop selectively at the will of the operator only at one or the other of its limits of movement toward and from the shoe bottom.
59. A machine of the class described having, in combination, a shoe support and a leveling roll relatively movable in directions lengthwise of a shoe on the support, power-operated means including a clutch for imparting to said leveling roll reciprocatory movements heightwise of the shoe into and out of engagement with the bottom of the shoe, manually operated means for controlling said clutch to enable the operator to stop said movements, and automatic means associated with said manually operated means to cause the roll to come to a stop only at one or the other of its limits of movement toward and from the shoe bottom.
60. A machine of the class described having, in combination, a shoe support and a leveling roll relatively movable in directions lengthwise of a shoe on the support, power-operated means including a manually controlled clutch for imparting to said leveling roll reciprocatory movements heightwise of the shoe into and out of engagement with the bottom of the shoe, a treadle for controlling said clutch to stop the movements of the roll at the will of the operator, and cam means associated with said treadle to cause the roll to come to a stop only at one or the other of its limits of movement toward and from the shoe bottom.
61. A machine of the class described having, in combination, a shoe support and a leveling tool relatively movable in directions lengthwise of a shoe on said support, power-operated means for operating said leveling tool to apply repeated pressure impulses to the bottom of the shoe, a manually operated member movable to start said power-operated means and arranged to continue said means in operation as long as said member is held in a predetermined position, and means arranged for use at will to lock said member in that position.
62. A machine of the class described, having, in combination, a shoe support and a leveling tool relatively movable in directions lengthwise of a shoe on said support, power-operated means for imparting to said leveling tool reciprocatory movements heightwise of the shoe, a treadle arranged to be depressed to start said power-operated means and to continue said means in operation as long as it is held depressed, and a device arranged for use at will to lock the treadle in depressed position.
63. A machine of the class described having, in combination, a shoe support and a leveling tool relatively movable in directions lengthwise of a shoe on said support, power-operated means for imparting to said leveling tool reciprocatory movements heightwise of the shoe, a treadle arranged to be depressed to start said power-operated means and to continue said means in operation as long as it is held depressed, a device arranged to lock said treadle in depressed position, and a member for controlling said device to release the treadle at the will of the operator.
- In testimony whereof I have signed my name to this specification.
